6 Claims. (Cl. 260—468)

1

The present invention relates to a process for producing vinyl esters of carboxylic acids.

A process for producing vinyl esters of carboxylic acids by reacting acetylene, at elevated temperatures and preferably elevated pressures, with carboxylic acids in liquid phase and in the presence of a small amount of a cadmium or zinc salt of a carboxylic acid as a catalyst, has been described in United States Patent No. 2,066,075 to Reppe.

While it is preferable to employ elevated temperatures and pressures in practicing the above-mentioned process, and, in fact, such reaction conditions are necessary if a satisfactory rate of reaction and yield are to be obtained, the inherent instability of acetylene under such reaction conditions has heretofore introduced numerous difficulties in practicing this process. In order to render the acetylene reasonably safe under the preferred reaction conditions, it has been necessary to dilute it sufficiently with inert gases, such as nitrogen, hydrogen, carbon monoxide, methane or ethane in order to preclude explosions. A mixture of 2 volumes of acetylene with 1 volume of nitrogen, hydrogen or another of the aforesaid gaseous diluents usually has been employed. This dilution of the acetylene with inert gaseous diluents has resulted in a substantial increase in the over-all pressure which is required and has materially lowered the rate of reaction and yield at any given reaction conditions. In addition to these and other undesirable process effects, it has substantially increased the size of the plant and auxiliary equipment required for carrying out the reaction.

We have now found that this reaction may be carried out at relatively lower pressures and with a relatively higher rate of reaction and yield under any given reaction conditions if the acetylene employed in the process is mixed with a sufficient amount of the vapors of a volatile, normally liquid, organic diluent to eliminate the danger of explosion in the manner described in our copending application Serial No. 621,620. When the acetylene is diluted in this manner with the vapors of a volatile, normally liquid, organic diluent, not only are the desired process effects of elimination of the dangers of explosion overcome and, at any given reaction conditions, the improvement in yield and rate of reaction obtained, but in addition, the capital cost of plant necessary for practicing the process may be substantially reduced.

In practicing the present invention, the acetylene is saturated or carbureted with the vapors

2

of a volatile, normally liquid, organic diluent in any desired manner. It is preferable to introduce into the acetylene the required amount of vapors of a volatile, normally liquid, organic diluent while the acetylene is at a relatively low pressure and/or temperature, i. e., conditions at which it is non-explosive, and thereafter compress it to the pressure desired for the reaction and, if necessary, heat it to the reaction temperature. However, by employing slow acting compressors and cooling during compression, it is possible to bring undiluted acetylene to a relatively high pressure with reasonable safety, and the vapors of the volatile, normally liquid, organic diluent may then be introduced into the compressed acetylene. While the particular method of introducing the diluent vapors into the acetylene does not, per se, form a part of the present invention, and numerous means for accomplishing this introduction have been described in our above-mentioned copending application, advantageously, the acetylene may be contacted with the desired diluent, while the diluent is in liquid phase and is maintained at such a temperature that the acetylene will take up or become carbureted with a sufficient amount of vapors of the diluent that it will be non-explosive at the reaction conditions to be employed. In practicing the present invention, it should be borne in mind that in order to preclude the possibility of explosion, not only should the acetylene which is supplied to the reaction be diluted with the vapors of a volatile, normally liquid, organic diluent but any unreacted acetylene removed from the reaction mixture should be similarly diluted so long as it is under an elevated pressure and/or temperature.

The volatile, normally liquid organic compound which is employed to dilute or carburize the acetylene may, in case the vinyl ester to be produced is that of a volatile organic acid, be the vapors of the acid itself or a volatile ester, which in turn may be a product of the reaction, if desired, thereof. In addition, practically any volatile organic compound which is inert under the conditions of the reaction may be employed as the diluent or carbureting agent. As suitable compounds for such use may be mentioned the lower aliphatic liquid hydrocarbons, such as aliphatic or cycloaliphatic hydrocarbons, for example, hexane, heptane, octane, cyclohexane and others, their isomers or mixtures thereof, for instance, volatile petroleum fractions, also many aromatic or naphthenic hydrocarbons, such as benzene, toluene, xylene and the like, and in ad-

dition, certain heterocyclic compounds. A wide variety of such compounds as ethers, esters, etc., may be employed as the diluent or carbureting agent. Thus, such compounds as diethyl ether and esters, such as ethyl acetate, also certain products of the reaction, if they are sufficiently volatile, for instance, vinyl acetate and the like are suitable. The particular amount of diluent which should be employed will, of necessity, vary with the reaction conditions to be used and also with the specific compound being employed as a diluent a sufficient amount of diluent or carburing agent being employed to preclude the possibility of explosions. The limits of explosability or the degree of dilution which is necessary may be determined readily for any particular conditions by simple preliminary test. Thus, for instance, acetylene gas, together with a predetermined amount of diluent vapor may be enclosed in a pressure vessel under test pressure and heated to the test temperature and any possible explosion initiated by means of an electrically heated wire provided within the pressure vessel. The reaction may be carried out in the presence of an inert liquid diluent or solvent which may be the same as or different from the diluent employed for the acetylene. As examples of suitable solvents may be mentioned aliphatic, aromatic or hydroaromatic hydrocarbons, such as benzene, petroleum fractions, toluene, xylene, cyclohexane, tetrahydronaphthalene, esters, for instance, the vinyl esters obtainable according to the present process, or such esters as methyl, ethyl, n-butyl, isobutyl or amyl acetate or butyrate.

When the acetylene, diluted with a sufficient amount of vapors of a volatile, normally liquid, organic diluent to preclude the possibility of explosion, is admixed with a carboxylic acid in the presence of a small amount of a suitable catalyst, and the reaction mixture maintained at predetermined reaction conditions, the acetylene readily reacts with the carboxylic acid to form vinyl esters. It appears that the probable course of reaction is in accordance with the following equation:

The process of the present invention is applicable to the production of vinyl esters of organic carboxylic acids. Suitable aliphatic carboxylic acids are, for example, formic, acetic, propionic, butyric, valeric, caprylic, lauric, palmitic, margaric, stearic, oleic, adipic, myristic, and sebatic acid. Suitable cyclic acids are, for example, aromatic carboxylic acids, such as benzoic acid, ortho-, meta- and para-toluic acids or abietic acid and the different isomers of naphthoic acid, also mixed aliphatic-aromatic acids, as for example, phenyl acetic acid, cinnamic acid, phenyl glycine and polybasic cyclic acids or their acid esters, such as phthalic acid and phthalic acid mono-alkyl esters, for example, mono-ethyl, normal or isobutyl esters; also cyclohydroxy carboxylic

acids, as for example, salicyclic acid or hydroxy naphthoic acid; and in addition, heterocyclic acids, such as pyridine and quinoline carboxylic acids, and hydroaromatic carboxylic acids, for example, hydrophthalic acid. Instead of pure acids, partially esterified acids or resins showing a high acid value, such as colophony, or mixtures of acids may be employed, as for example, the acids obtainable by saponification of natural fats and fatty oils containing esters and all fatty acids or the mixtures of acids obtainable by the partial oxidation of selected petroleum fractions, for instance, paraffin wax, and the like.

The reaction is catalyzed by zinc and cadmium salts of organic acids, and suitable catalysts are such compounds as zinc acetate, zinc stearate, zinc benzoate or the corresponding cadmium salts. These salts may be added, as such, to the acid treated with acetylene or they may be prepared by dissolving the zinc or cadmium oxides in the acids to be employed. In practicing the present process, it is preferable to employ at least 7.5% of catalyst, calculated as ZnO or CdO with reference to the acid employed, and generally speaking, the quantity of the catalyst is between 0.5 and about 5%.

The vinyl esters produced in accordance with the present invention may be recovered in any suitable manner from the reaction mass, for instance, by extraction with suitable solvents or by distillation under vacuum, if necessary. Various polymerization inhibitors, such as hydroquinone, naphthols, or amines may be added during the distillation or on subsequent storage of the vinyl esters. The vinyl esters obtained according to this invention may be polymerized by the usual methods.

The following examples will further illustrate how this invention may be carried out in practice, but the invention is not restricted to these examples:

Example 1

Acetylene at a pressure of 4 pounds per square inch, free from moisture and other impurities, is passed through a bath of acetic acid maintained at 118°C . The acetylene is saturated with acetic acid and is then compressed to 45 pounds per square inch and then heated to a temperature of 145°C . It is then introduced into the bottom of a tower filled with glacial acetic acid, held at a temperature of 170°C . in which is dissolved approximately 4% by weight of zinc acetate. The acetylene reacts rapidly with the acetic acid, in accordance with the following equation:

and vinyl acetate, along with unreacted acetic acid and acetylene are continuously withdrawn from the reaction zone, while fresh acetic acid and catalyst, if necessary, are continuously introduced into the reaction zone. The pressure on the products withdrawn from the reaction zone may be released and the acetylene separated therefrom, and thereafter, the vinyl acetate separated from the acetic acid by fractional distillation, vinyl acetate being obtained as a colorless liquid boiling at 73°C . in 85-95% yield.

Example 2

Acetylene at a pressure of 4 pounds per square inch is passed through a bath of cyclohexane, maintained at 79°C ., and becomes saturated therewith and is then compressed to a pressure

of 45 pounds per square inch and heated to a temperature of 145° C. It is then passed into a closed reaction vessel, filled with valeric acid, containing about 2.5% zinc acetate and maintained at a temperature of approximately 170° C. The acetylene reacts readily with the valeric acid to produce vinyl valerate in accordance with the following equation:

During the reaction, acetylene, diluted with cyclohexane, is continuously removed from the reaction zone and fresh diluted acetylene introduced thereinto. When the acetylene is no longer absorbed, the reaction mixture is allowed to cool and is then filtered to remove zinc valerate. The filtrate is then subjected to fractional distillation, cyclohexane first being distilled off, and thereafter, vinyl valerate boiling at 132-134° C. at atmospheric pressure is obtained in 93-95% of the theoretical yield.

As compared with the above described process, under similar conditions, by employing acetylene diluted with nitrogen in the ratio of 2:1, a temperature of 180° C. is required and a pressure of 300-375 pounds per square inch.

Example 3

Acetylene at 4 pounds per square inch is passed through a bath of cyclohexane maintained at 79° C., and becomes saturated therewith and is then compressed to 45 pounds per square inch and heated to 145° C. It is then introduced into a closed reaction vessel charged with 200 pounds oleic acid, 40 pounds cyclohexane and 14 pounds of zinc acetate from which oxygen has been removed by flushing with nitrogen and the nitrogen removed by evacuation. The mixture in the reaction vessel is maintained at 160° C. The acetylene readily reacts with the oleic acid to form vinyl oleate in accordance with the following equation:

During the reaction, unreacted acetylene and cyclohexane may be continuously withdrawn from the reaction zone while fresh diluted acetylene is continuously introduced thereinto. When the theoretical amount of acetylene has been absorbed, the reaction mixture is then allowed to cool, then filtered to remove zinc acetate and the filtrate fractionally distilled. After separating off the cyclohexane, vinyl oleate boiling at 173-175° C. at 2 mm. pressure is obtained in 90-95% yield.

We claim:

1. In a process of producing vinyl esters wherein acetylene is introduced into a reaction zone and reacted therein with an organic carboxylic acid maintained in said reaction zone under elevated conditions of temperature and pressure at which the acetylene is normally explosive, the method of eliminating the danger of acetylene explosion which comprises contacting the acetylene which is supplied to said reaction zone while it is under non-explosive conditions of temperature and pressure with a volatile normally liquid organic compound selected from the group consisting of volatile organic liquid diluents which are inert in said reaction and volatile organic acids employed in said reaction, said contacting being effected while said volatile normally liquid organic compound is in liquid phase and is maintained at such a predetermined temperature that the acetylene on contact therewith becomes sat-

urated with the vapors of said volatile normally liquid organic compound in such an amount as to form a mixture of acetylene and such vapors in such predetermined ratio that said mixture is non-explosive at said normally explosive reaction conditions, adjusting the pressure and temperature of the thus formed mixture to said normally explosive reaction conditions, introducing the thus obtained mixture into said reaction zone while maintaining it at a temperature above that at which said vapors will condense and therein effecting the desired reaction between said acetylene and said organic carboxylic acid to produce a vinyl ester and recovering the same.

15. 2. In a process of producing vinyl esters of volatile organic carboxylic acids wherein acetylene is introduced into a reaction zone and reacted therein with a volatile organic carboxylic acid maintained therein under elevated conditions of temperature and pressure at which the acetylene is normally explosive, the method of eliminating the danger of acetylene explosion which comprises contacting the acetylene which is supplied to said reaction zone while it is under non-explosive conditions of temperature and pressure with a body of said volatile organic carboxylic acid in liquid phase and maintained at such a predetermined temperature that the acetylene on contact therewith becomes saturated with the vapors of said volatile organic carboxylic acid in such an amount as to form a mixture of acetylene and such vapors in such predetermined ratio that said mixture is non-explosive at said normally explosive reaction conditions, adjusting the pressure and temperature of the thus formed mixture to said normally explosive reaction conditions, introducing the thus obtained mixture into said reaction zone while maintaining it at a temperature above that at which said vapors will condense, effecting the desired reaction between said acetylene and said volatile organic carboxylic acid in said reaction zone to produce a vinyl ester and recovering the same.
30. 3. A process as defined in claim 2, wherein the volatile organic carboxylic acid specified is acetic acid and the vinyl ester produced is vinyl acetate.
45. 4. In a process of producing a vinyl ester wherein acetylene is introduced into a reaction zone and reacted therein with an organic carboxylic acid under elevated conditions of temperature and pressure at which the acetylene is normally explosive, the method of eliminating the danger of acetylene explosion which comprises contacting the acetylene supplied to said reaction zone while it is under non-explosive conditions of temperature and pressure with a non-explosive volatile normally liquid organic compound which is inert to both the acetylene and the organic acid under the conditions of reaction, while said volatile normally liquid organic compound is in liquid phase and is maintained at such a predetermined temperature that the acetylene on contact therewith becomes saturated with the vapors of said normally liquid organic compound in such an amount as to form a mixture of acetylene and such vapors in such predetermined ratio that said mixture is non-explosive at said normally explosive reaction conditions, adjusting the temperature and pressure of the thus formed mixture to said normally explosive reaction conditions, introducing the thus obtained mixture into said reaction zone while maintaining it at a temperature above that at which said vapors will condense and therein effecting the desired reaction between the acetylene and said organic carboxylic

acid to produce a vinyl ester and recovering the same.

5. A process as defined in claim 4, wherein the organic carboxylic acid specified is valeric acid and the vinyl ester produced is vinyl valerate.

6. A process as defined in claim 4, wherein the organic carboxylic acid specified is oleic acid and the vinyl ester produced is vinyl oleate.
